UNITED STATES PATENT OFFICE.

JOSIAH S. TUTTLE AND CHARLES L. COOKSON, OF KANSAS CITY, MISSOURI, ASSIGNORS TO PANAMA HAY PRESS CO., OF KANSAS CITY, MISSOURI, A CORPORATION OF MISSOURI.

BALING-PRESS.

No. 814,251.

Specification of Letters Patent.

Patented March 6, 1906.

Application filed March 15, 1905, Serial No. 250,288.

To all whom it may concern:

Be it known that we, JOSIAH S. TUTTLE and CHARLES L. COOKSON, citizens of the United States, residing at Kansas City, in the 5 county of Jackson and State of Missouri, have invented certain new and useful Improvements in Baling-Presses, of which the following is a specification.

Our invention relates to baling-presses; and 10 our object is to produce a baling-press of the half-cycle type having a capacity under ordinary conditions of eight to ten tons per day, which can be readily operated by one horse.

A further object is to produce a baling- 15 press of the character mentioned which is of simple, strong, durable, and comparatively cheap construction.

A still further object is to produce a machine of this character in which the sweep as 20 the power-stroke is completed co-operates with the driver in turning the horse around, and thereby facilitates the baling operation.

The invention consists, essentially, of a baling-case, a reciprocatory plunger therein, 25 a plunger-beam pivoted for lateral movement to the plunger, a power-shaft pivoted to the casing for horizontal movement forward of the plunger and provided with a power-arm and a sweep at opposite sides and a swinging 30 link pivotally connecting the power-arm and the front end of the plunger-beam and adapted to swing from one side of the power-arm to the other in order to permit the plunger-beam to alternately recoil at opposite sides of 35 the power-shaft, and thus permit a power-stroke of the plunger to be made with each movement of the sweep and without requiring the horse to be backed up at any time during the operation of the machine.

The invention further consists in certain 40 novel and peculiar features of construction and organization, as will be readily understood by reference to the accompanying drawings, in which like parts are indicated by the 45 same reference-numerals throughout the several views.

Figure 1 is a perspective view of a baling- 50 press embodying our invention. Fig. 2 is a horizontal section taken on the line II II of Fig. 4 with the movable parts occupying a different position from that shown by Fig. 1. Fig. 3 is a horizontal section taken on the line III III of Fig. 4, but with the movable parts

occupying a different position from that indicated by Figs. 1 and 2. Fig. 4 is a view, 55 partly in side elevation and partly in central longitudinal section, with the movable parts occupying the position shown by Fig. 3, Fig. 4 being also broken away to disclose features otherwise hidden. Fig. 5 is a horizontal section taken on the line V V of Fig. 1. Fig. 6 is a vertical transverse section taken on the line VI VI of Fig. 1. Fig. 7 is a vertical section on the line VII VII of Fig. 2.

In the said drawings, 1 indicates a pair of 60 parallel runners connected at intervals by cross-bars 2, two or more of which are preferably provided with loops 3, through which stakes are adapted to be driven to anchor the machine reliably during the baling operation. 70

4 indicates angle-plates secured to the cross-bars and fastening rigidly thereto the parallel angle-irons 5, connected by a bottom plate 6, extending the full length of the angle-irons, by preference, and forming the bottom 75 of the baling-case.

7 indicates plates forming the side walls of the baling-case, and secured to said plates, and projecting forwardly therefrom are angle-irons 8, inverted with respect to angle-irons 5 and parallel therewith, similar angle-irons 9 in longitudinal alinement with angle-irons 8 being secured rigidly to plates 7 and projecting rearwardly therefrom. Angle-irons 8 are connected by front top plate 10 80 and angle-irons 9 by the top plate 11, the opening 12 between plates 10 and 11 constituting the feed-opening for the hopper, composed of side walls 13 and front wall 14, rigidly connecting the side walls, which at 90 their rear ends are formed with outwardly-projecting ears 15, connected by a cross-bar 16, clamped down tightly upon the front ends of angle-irons 9 by vertical bolts 17, extending through said bar and through the angle-plates 4 and cross-bar 2 in vertical alinement therewith, the upper ends of the bolts being engaged by clamping-nuts 18, so that the baling-case at such point shall be absolutely rigid. 100

19 indicates spring-actuated retainers of the type shown or of any other suitable or preferred type mounted on bolts 17 and projecting into the path of the material being baled for the purpose of snapping back of 105 each charge of the material that is com-

pressed to prevent the same from springing back after the recoil of the plunger and interfering with the proper entrance into the baling-case of the subsequent charge of baling material. To coöperate with these retainers, 5 a transverse rock-shaft 20 extends across the rear end of the baling-case near its upper margin and is journaled in the side walls thereof, and provided within said case with a tucker 21 of the type shown or its equivalent, 10 a crank-arm 22, secured to one of the outer ends of the shaft, being connected by a retractile spring 23 with a fixed point of the machine—viz., with the proximate ear of the 15 hopper, as shown clearly in Fig. 5, the tendency of said spring being to hold the tucker in a vertically-pendent position.

The compression end of the press rearward of the side walls 7 is embraced by the U-shaped bolt 24, extending upward through a 20 cross-bar 25, mounted upon the angle-irons 9 and plate 11, and engaging the upper ends of said bolt are hand-nuts 26, said nuts permitting the discharge end of the compression-chamber to be contracted for the usual purpose. 25

27 indicates channeled cross-bars inverted with respect to each other, one connecting the angle-irons 5 and the other the angle-irons 8 30 and each provided with a central hub portion 28. 29 is a cylindrical piece of pipe mounted in said hub portions, and 30 a bolt extending through the bottom of the channel-bars 27 and said pipe and engaged at its upper end 35 by a washer 31 and a clamping-nut 32, this construction affording a strong and rigid brace against vertical springing movement of the front portion of the press. 33 indicates a power-shaft journaled upon the pipe between 40 said hub portions 28 and provided centrally with a socket-arm 34, receiving the inner end of the sweep 35, the latter being bolted reliably in the socket-arm, as at 36. 37 is a clip swiveled to the opposite end of the 45 sweep, and 38 is an eye or its equivalent connecting said clip with a swingletree 39, to which the horse is adapted to be hitched. Projecting rigidly from the power-shaft are the power-arms 40, equipped with bolts 41, 50 slidingly engaging slots 43 of links 42, arranged at the inner sides of arms 40. 44 is a bolt connecting the opposite or outer ends of the links, and journaled on said bolt is an antifriction-roller 45. Pivoted on said bolt 55 above and below the roller are the arms 46 of the bifurcated front end of the plunger-beam 47, the opposite end of the plunger-beam being horizontally bifurcated, as at 48, and engaging the lug 50 of the plunger 51 of the type 60 shown or of any other suitable or preferred type, a vertical bolt 52, carried by the plunger, extending through said lug and plunger-beam, so as to pivotally unite them together for relative horizontal movement. A link 53, mounted 65 on said bolt, is connected by a retractile

spring 54 to the lower cross-bar 27 for the purpose of insuring the proper recoil of the plunger, and in order to prevent baling material from being dropped into the baling-case forward of the plunger an apron 55 is 70 hinged, as at 56, to the plunger and carries a rod 57 at its opposite end engaging a grooved guideway 58. As a means for limiting unnecessary lateral movement of the plunger-beam and for providing a horizontal support 75 for the same, so as to relieve the power-arms 40 and links 42 of the weight of said beam, we provide an H-shaped frame consisting of vertical arms 59 and the horizontal arm 60, the former connecting the vertically-aligned angle-irons 5 and 8 and the latter underlying the beam. 80

The practical operation of the machine is as follows: Assuming the parts to be in the position shown in Fig. 1 and the horse traveling in the direction indicated by the arrow, Fig. 1, it will be seen the leverage decreases until the parts have assumed the relative positions shown in dotted lines, Fig. 2; but it will be understood that said gradual decrease 90 of leverage is attended by a rapid movement of the plunger, opposed by little resistance on the part of the loosely-bunched baling material in the baling-chamber. The continued movement of the sweep in the same direction 95 eventually disposes the parts in the position shown in full lines, Fig. 2, and it will be noted in this connection that as the baling material becomes more compactly bunched, and therefore offers increasing resistance to 100 the movement of the plunger, the speed of the latter gradually diminishes and its leverage is proportionately increased, the leverage increasing gradually while the parts are traveling from the position shown in dotted lines 105 to the position shown in full lines, Fig. 2. Said movement of the sweep still continuing continues the power stroke of the plunger-beam, the movement thereof gradually decreasing in speed and increasing in leverage. 110 When the parts have assumed the positions shown in Fig. 3, the full compression-stroke has been made, and immediately thereafter the movement of the sweep results in the link pulling the free end of the plunger-beam to 115 the opposite side of the power-shaft to that which it originally occupied, and in this connection it will be noted that friction between the power-shaft and the beam is reduced to a minimum because roller 45 rolls 120 around upon the power-shaft while the heaviest work of the plunger is in progress and at the beginning of the recoil movement. The recoil takes place, as stated, at the opposite side of the power-shaft from that originally 125 occupied by the beam, the latter recoiling through the space between the power-arms, as will be readily understood by reference to Figs. 3 and 4 particularly, this action being 130 permitted because of the pin-and-slot connec-

tion between the links and power-arms, the links sliding outward under the recoiling movement and the resistance of the power-shaft to the movement of the roller 45 and 5 in the opposite direction as soon as said power-shaft has been passed. At the end of the recoil the parts occupy exactly the reverse position to that shown by Fig. 1, because as the tripping action is about to take 10 place the driver turns the horse outward. As this turning operation is in progress the recoil takes place, and the force of the recoil causes the sweep to, in effect, jump toward the press, and therefore assist in causing the clip to 15 swing to the front side of the tongue, as disclosed by Fig. 1. The back pull thus imposed on the horse tends to cause him to wheel around of his own accord and face in the opposite direction to that which he traveled in 20 making the preceding stroke. It will thus be seen that the horse always walks forward in operating the machine, and that with each what is generally termed "half-cycle" movement a compression-stroke and recoil occurs. 25 It will also be observed that while the power-stroke is taking place a tensile strain is on the links and that as the recoil takes place the front end of the plunger-beam moves toward and then from the outer end of the 30 power-arms, the slotted relation of the links permitting such action, and in this connection it is desired to call attention to the fact that a chain or other flexible connection between the power-arms and the plunger-beam will 35 give the same effect as the slotted link, and is therefore a mechanical equivalent of the latter.

From the above description it will be apparent that we have produced a baling-press 40 embodying the features of advantage enumerated as desirable in the statement of invention and which obviously is susceptible of modification in its form, proportion, detail, construction and arrangement of the parts

without departing from the principle of construction involved 45

Having thus described the invention, what we claim as new, and desire to secure by Letters Patent, is—

1. In a baling-press, a power-shaft having 50 superposed trip-arms, a plunger-beam capable of passing between the arms, and a pair of links capable of swinging through the space between said arms and pivotally connected to the latter and the beam. 55

2. In a baling-press, a power-shaft having superposed trip-arms, a plunger-beam capable of passing between the arms, and a pair of 60 links capable of swinging through the space between said arms and pivotally connected to the latter and the beam, and longitudinally slid able on the arms.

3. In a baling-press, a power-shaft having superposed trip-arms, a plunger-beam capable of passing between the arms, and a pair of 65 links capable of swinging through the space between said arms and pivotally connected to the latter and the beam, and having longitudinal slots engaging the pivots connecting them with the arms. 70

4. In a baling-press, a power-shaft having superposed trip-arms, a plunger-beam capable of passing between the arms, a pair of links capable of swinging through the space between said arms and pivotally connected 75 to the latter and the beam, and having longitudinal slots engaging the pivots connecting them with the arms, and an antifriction-roller on the pivot connecting the links and beam, to roll against the shaft. 80

In testimony whereof we affix our signatures in the presence of two witnesses.

JOSIAH S. TUTTLE.
CHARLES L. COOKSON.
